UNITED STATES PATENT OFFICE.

WILLIAM S. SUTTON, OF ROCKFORD, ILLINOIS, ASSIGNOR TO HOUSTON MANUFACTURING COMPANY, OF ROCKFORD, ILLINOIS, A CORPORATION OF ILLINOIS.

DESIGN FOR A FRAME FOR VACUUM-CLEANERS.

45,405.

Specification for Design.

Patented Mar. 10, 1914.

Application filed November 4, 1911. Serial No. 658,586. Term of patent 14 years.

To all whom it may concern:

Be it known that I, WILLIAM S. SUTTON, a citizen of the United States, residing at Rockford, in the county of Winnebago, State of Illinois, have invented a new, original, and ornamental design for Frame for Vacuum-Cleaners, of which the following is a specification, reference being had to the accompanying drawing, forming a part thereof.

The figure is a side elevational view showing my new design.

I claim:

The ornamental design for a frame for a vacuum cleaner, as shown.

WILLIAM S. SUTTON.
